DRESSER COMPENSATING MECHANISM FOR
GRINDING MACHINESAugust F. Markus, Detroit, Mich., assignor to Ex-
Cell-O Corporation, Detroit, Mich., a corpora-
tion of Michigan

Application August 28, 1944, Serial No. 551,477

13 Claims. (Cl. 51—95)

The present invention is intended for application to grinding machines such, for example, as thread grinders, and has particular reference to grinding machines incorporating that general class of mechanisms known as automatic dressing compensators which serve to modify automatically the relative displacement of grinding wheel and work by an amount requisite to compensate for the diminishment in wheel size necessarily incident to each truing or dressing of the same.

The general aim of the invention is to provide in a grinding machine such a mechanism, and coacting size control device, embodying a novel and simplified combination of elements such as to afford high precision results while utilizing rugged, simple and comparatively inexpensive parts.

In carrying out the present invention, I preferably utilize the displacement of a nut, in a direction axially of a shaft on which it is threaded, to move the work support relative to its associated grinding wheel. The movement of the nut may be accomplished in such case either by shifting the shaft bodily in an axial direction or by revolving such shaft so that the nut is threaded along it. A more specific object of the present invention is to provide a novel and improved arrangement in which bodily axial shifting of such shaft is effected in response to movement of a dresser mechanism, whereas rotation of the shaft is accomplished in response to actuation of a size control device. Accordingly, movement of the nut for effecting both dressing compensation and size control adjustments of the work support, and without any interference of either adjustment with the other, may be made despite the fact that both such adjustment movements are imparted to the work support through the same shaft.

Considered in a somewhat different aspect, it is an object of the present invention to provide a grinding machine embodying work and tool supports with a dresser support mechanically interconnected to one of the first-mentioned pair for movement in unison with it in reference to the other of the pair in such manner as to effect compensation for dressing, together with means including a piston and cylinder type actuator interposed in such mechanical interconnection for effecting rapid shift of said one support with reference to the other of the first-mentioned pair without moving said dresser support.

Further objects and advantages of the invention will become apparent as the following de-

scription proceeds, taken in connection with the accompanying drawings in which:

Figure 1 is a front elevation of a thread grinding machine embodying the present invention.

Fig. 2 is an enlarged detail sectional view taken longitudinally through the work support of the machine of Fig. 1.

Fig. 3 is a sectional view taken from front to rear through the upper portion of the machine substantially along the lines 3—3 in Fig. 1.

Fig. 4 is a more or less diagrammatic view similar to Fig. 3 but showing the dresser supporting arrangement in section.

Fig. 5 is a detail sectional view taken substantially along the line 5—5 in Fig. 4.

Fig. 6 is a detail perspective view of a portion of the adjustable mount for the wheel support.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the exemplary embodiment of the invention illustrated in the drawings, the thread grinding machine there shown comprises a base or bed 10 on the top of which are work and grinding wheel supports 11 and 12, respectively (Fig. 1). The latter carries a rotatively driven grinding wheel 14. In the particular machine chosen for purposes of illustration, both the relative traversing motion of such supports axially of the work in timed relation with the latter's rotation, and the incremental transaxial relative infeed movement of such supports, normally incident to thread grinding, are accomplished by imparting corresponding appropriate motions to the work support 11, the wheel support 12 remaining stationary throughout the normal operation. In its broader aspects, however, the invention is applicable to grinding machines in which that same relativity of motion is accomplished in other manners.

The present invention is concerned primarily with an arrangement for modifying automatically the transaxial displacement of grinding wheel and work to compensate for diminutions in grinding wheel diameter incident to dressing or truing of the wheel by suitable truing means such as the dresser indicated at 15 (Fig. 3). In the illustrative machine such compensating motion is im-

parted to the work support and, is moreover, accomplished, as will hereinafter appear in detail, through the same operating connections which are utilized in effecting its normal transaxial motion of the work support for infeed purposes and the like.

In the instant embodiment the work support 11 comprises a main frame 16 (see Fig. 2) translatable along a pair of aligned guide bars 17, 18 axially of a work piece W carried between centers 19, 20 on the support. The frame 16 is rocked or pivoted about these same guide bars 17, 18 to move the work transaxially toward and from the grinding wheel 14. To suitably mount the frame for such motions, depending feet 21, 22 integral with the frame 16 are journaled on respective ones of the guide bars 17, 18. The opposite end portions of the latter are fixed in respective pairs of lugs 23, 24 and 25, 26 on the machine base 10.

One of the work-receiving centers 20 (Fig. 2) is carried by a tailstock 27 adjustably slidable along the frame 16 and adapted to be clamped thereto, whereas the other center 19 is fixed in the end of a work-rotating spindle 28, the drive for which will hereinafter appear. The forward end of such spindle is journaled in an antifriction bearing 29 mounted in a wall 30 rising integrally from the frame 16 and forming the front face of a headstock casing. Such casing is completed by a detachable casing member 31 having a tubular extension 32 projecting therefrom coaxially with the spindle and carrying an antifriction bearing 33 supporting the intermediate portion of the spindle.

The work support frame 16 rests upon, and is translatable axially along, an intermediate support 34 (Figs. 2 and 3). This intermediate support or apron comprises a generally rectangular-shaped casting pivoted coaxially with the work support frame 16 on the same guide bars 17 and 18 which carry the latter. Upon reference to Fig. 2 it will be seen that lugs 35 and 36 on the intermediate support 34 are journaled on respective ones of these guide bars. The intermediate support is, unlike the work support frame, restrained against axial movement, however. A pair of yoke-shaped legs 37 rigid with the intermediate support 34 depend from it and slidably receive laterally projecting trunnions 38 on a nut 39. The intermediate support 34, together with the work support frame 16 resting on it, is thus rocked about its pivot generally transaxially of the grinding wheel 14 upon endwise movement of the nut 39.

The nut 39 is threaded on a screw 40 formed intermediate the ends of a shaft 41, the nut itself being restrained against rotation by engagement of its flat sides with the legs 37 between which it is positioned (see Fig. 2). The nut may thus be moved endwise either by rotation of the screw 40 or by bodily endwise movement of such screw. In the present instance the screw 40 is revolved to move the nut 39 endwise for rocking the work support for size control purposes, whereas the screw 40 is moved endwise to shift the nut and thus the work support for compensating purposes.

Various suitable size control devices may be used for revolving the screw 40, such a device being designated herein generally by the numeral 42. Such device includes a size control handwheel 43 which may be revolved manually for turning the screw 40, the handwheel being splined to the latter to permit endwise movement of the screw with reference to the handwheel. If desired, a suitable ratchet or other power operated

drive mechanism (not shown) may be housed in the casing 44 to turn the screw incrementally in timed relation with the reciprocation of the work support 11. A suitable mechanism for the purpose is disclosed in Guenther Brinkmann application Serial No. 435,224, filed March 18, 1942, and assigned to Ex-Cell-O Corporation, assignee of this present application, but since the same constitutes per se no part of the present invention, it need not be illustrated in detail here.

To shift the screw 40 endwise proportionately to changes in wheel diameter incident to dressing of the latter, the screw is mechanically connected to a dresser supporting frame or bracket 45 (Figs. 3 and 4). The frame 45 is rigidly bolted to the underside of a dresser approach slide 46 and is movable bodily with the latter toward and from the grinding wheel in a direction generally transaxial of such wheel. To mount the slide 46 for such movement, rails 47 (see Fig. 5) are fixed in horizontal position on an upstanding rearwardly disposed portion of the wheel support 12 and have longitudinally extending grooves 48 therein. Secured to the underside of the slide 46 is a pair of rails 49 longitudinally grooved as indicated at 50. Antifriction ball elements 51 are received between the opposed pairs of grooves 48, 50, the latter constituting raceways for the balls.

Any suitable form of dresser mechanism 15 including one or more diamond dresser points 52 may be mounted on the approach slide 46, a suitable construction being illustrated in Gilbert Stewart Patent No. 2,311,263, issued February 16, 1943. Reference may be made to the latter patent for details of construction. For the present suffice it to note that a dresser drive motor 53 operates through a cam 54 to cause the dresser point 52 to execute a predetermined cycle of movement with reference to the approach slide 46 in moving the dresser point into engagement with the periphery of the grinding wheel 14 and thence away from the latter into an inoperative position again. The mean location of the path of the dresser point in each such cycle, with reference to the grinding wheel, is determined by the location of the approach slide 46 and the latter is, accordingly, advanced incrementally preparatory to each cycling of the dresser.

A dresser feed screw 55 (Fig. 4) is provided for shifting the dresser frame 45 and its attached approach slide 46 toward and from the grinding wheel. For such purpose the screw is threaded in a nut 56 rigid with the frame 45 and is journaled in an upstanding rear portion 12a of the wheel support 12, the screw being restrained against endwise movement. A dresser feed control wheel 57 fixed to the screw 55 may be used in rotating the latter manually. If desired, provision may also be made for effecting step-by-step turning of the screw 55 in timed relation with the cycling of the dresser mechanism 15 as, for example, through the use of a control arrangement for such purpose such as that disclosed in Ira J. Snader Patent No. 2,251,961, issued August 12, 1941. As indicated herein in Fig. 4, a ratchet wheel 58 may be fixed to the screw 55 and arranged for actuation by a pawl 59 carried by an oscillatable pawl carrier 60, the length of the angular distance through which the ratchet wheel is advanced upon each stroke of the pawl being determined by a pawl guard 60 adjustably held in position by a thumb screw 61. A reciprocable plunger 62 may serve to oscillate the pawl carrier 60 through use of a control ar-

angement like that disclosed in said Snader patent, one stroke being imparted to the pawl preparatory to each cycling of the dresser mechanism.

As to the mechanical connections between the dresser supporting frame 45 and the shaft 41 of the screw 40, it will be observed upon reference to Fig. 4 that a hydraulic piston and cylinder type actuator 63 is interposed between these elements, the same being provided for effecting quick retraction of the work with reference to the grinding wheel. This actuator includes a cylinder 64 connected by dovetail guides 65 with the dresser supporting frame 45 in order that the latter may be adjusted horizontally (i. e., in a direction axially of the work) with reference to the cylinder. Slidable in the cylinder 64 is a piston 66 having a socketed end 67 receiving the spherical opposed end of the screw shaft 41. Assuming pressure fluid to be supplied to the cylinder 64 through either of the ports 68, 69 and exhausted through the other, it will be seen that the dresser supporting frame 45 and screw 40 are rigidly connected for movement in unison. Thus, upon each incremental rotation of the dresser feed screw 55 to approach the dresser supporting frame 45 toward the grinding wheel, the cylinder 64 is correspondingly thrust to the left (as viewed in Fig. 4) carrying with it the shaft 41 and screw 40. The work piece W is thereby rocked toward the grinding wheel 14 a corresponding increment of distance, calculated through suitable dimensioning of the parts, to relocate the work with reference to the wheel in precisely its previous position after the wheel has been diminished in diameter by truing.

The purpose of providing the dovetail guides 65 and socket joint 67, 41 at opposite ends of the hydraulic actuator 63 is to accommodate bodily adjustment of the wheel support 12 (together with the dresser mechanism mounted thereon) both longitudinally of the work and angularly with reference to the latter. Such longitudinal adjustment is provided in order to locate the grinding wheel at preselected points along the length of the work whereas the angular adjustment is used in locating the wheel for a desired helix angle for the thread ground on the work. With regard to the latter, it will be understood that the required range of adjustment is rather small, being of the order of five degrees in the illustrated machine.

To mount the wheel support 12 for adjustment both longitudinally of the work and angularly with reference thereto, as noted above, an inclined flat surface 88 is machined on the bed 10 and an opposed parallel surface 89 provided on the wheel support 12. A block 78 having parallel flat faces is interposed between the surfaces 88, 89. This block is releasably clamped to the base 10 by bolts 71 having heads received in T-slots 72 extending longitudinally of the surface 88 (see Fig. 6), and a key 73 guides the block accurately for adjustment longitudinally of such surface 88. Similarly, the wheel support 12 is releasably secured by bolts passing therethrough (not shown) with their heads received in arcuate T-slots 74 in the block 78, angular adjusting movement of the wheel support with reference to the block 78 being guided by an arcuate key 74a. Upon either longitudinal or angular adjustment of the wheel support 12, the dresser mechanism 15 and its supporting arrangement 45, 46 move bodily with the wheel support so that the dresser mechanism is positionally un-

disturbed with reference to the grinding wheel 14. Movement of the dresser frame 45 laterally or, in other words, longitudinally of the work, is accommodated by the dovetail guide 65, whereas its angular movement is accommodated by the ball and socket joint 67, 41.

In the operation of the grinding machine disclosed, pressure fluid (from some suitable source, not shown) is supplied to the cylinder 64 through the port 69 to thrust the screw shaft 41 leftward, thereby rocking the work piece W quickly toward the grinding wheel 14. Having thus approached the work closely adjacent the grinding wheel, the work support frame is reciprocated back and forth axially of the work in timed relation with rotation of the latter. In the course of such reciprocation the screw 40 is turned step by step as, for example, after each pass of the work, until a thread of preselected depth has been ground in the work piece. At the conclusion of the grinding operation pressure fluid is admitted to the retract cylinder port 68 and exhausted through the port 69, thereby permitting the work support to swing gravitationally outward away from the grinding wheel while thrusting the screw shaft 41 to the right. It will be perceived that the hydraulic actuator 63 serves to rock the work support between alternate limit positions and that the size control mechanism 30 alters the displacement of the work support with reference to the grinding wheel 14, movement of the dresser supporting frame 45 also serving to alter or further modify such displacement.

At selected points in the grinding operation or after one or more complete grinding operations, the grinding wheel 14 is trued. For that purpose the work piece W is temporarily retracted from contact with the grinding wheel 14 by the retract actuator 63 and the dresser feed screw 40 55 turned to advance the dresser supporting frame 45 a predetermined increment of distance. Thereafter the dresser mechanism is operated, causing the dresser point or points 52 to execute a predetermined cycle of movement in which they true or dress the periphery of the grinding wheel and in doing so reduce it to a new diameter, the magnitude of the latter being determined by the position of the dresser supporting frame 45. Coincident with the advance of the dresser supporting frame 45, the screw shaft 41 is thrust to the left, thereby rocking the work piece W incrementally toward the grinding wheel a proportionate distance. Consequently the position of the work with reference to the grinding wheel is the same after each dressing of the latter has been completed as it was at the completion of the preceding dressing operation.

In so far as the present invention is concerned, various specific forms of work support may be employed as well as drive arrangements for rotating and translating the work. The particular form here shown is that described and claimed in my copending application Serial No. 542,719, filed June 29, 1944. Accordingly, simply a brief identification of the elements of the drive arrangement will suffice for present purposes, the principal elements of the illustrated structure having been previously noted. Upon reference to Fig. 2 it will be seen that the work supporting spindle 28 is revolved by a gear 80 integral with a sleeve 81 fixed to the spindle. Such gear meshes with a gear 82 carried by a shaft 83 splined at 84 to a shaft 85 carrying a gear 86. The latter gear meshes with a gear 87 coaxial with the guide rod 17, being carried on a shaft

88 extending through the latter. The spline connection at 84 accommodates translation of the work supporting frame 16 while retaining the drive connections intact and similarly the rolling of the gear 86 about the gear 87 retains the same in mesh during rocking of the work supporting frame toward and from the grinding wheel. The shaft 88 is driven from a motor 89 on the base of the machine (Fig. 1) through a belt 90 connected by a pulley 91 with a worm 92 (Fig. 2) meshing with a worm wheel 93 rigid with the end of the shaft 88.

Axial translation of the work in timed relation with its rotation is accomplished through the use of a master lead screw 94 (Fig. 2) keyed to the work spindle 28 and threaded in a nut 95. The latter nut is fixed to the end of a sleeve 96 which normally remains stationary within a housing or head 97. The latter head has a depending foot 98 journaled on the guide rod 17 in order that the head 97 may rock about the axis of the guide rod coincidentally with the rocking motion of the main work supporting frame 16. A block 99 secured to the head 98 on the side of the supporting lug 23 opposite the foot 98 coacts with the latter, however, to restrain the head 97 against translation axially of the guide rod. The tubular extension 32 on the housing 31 of the main work support is telescoped within the sleeve 96 and thus retains the head 97 and frame 98 in angular coincidence about the axis of the guide rod 17 while permitting relative displacement of the same axially of such guide rod. Rotational adjustment of the sleeve 96 within the head 97 to determine the point of lead pick-up is accomplished by a transverse screw 100, adapted to be turned by a handwheel 101, and meshed with an annular series of worm gear teeth 102 formed in the periphery of the sleeve.

Provision may also be made if desired for accommodating the motion of the work to taper grinding, relief grinding, etc. So long as these motions are imparted through movement of the work supporting frame 16 relative to the intermediate support 34, the latter remains unaffected and there is consequently no change required in the compensating mechanism. In the illustrated arrangement (Figs. 1 and 3) a bar 103 is clamped to the front of the frame 16 in adjustably variable inclined position and rests the overcharging weight of the frame 16 on the nose of a pin 104. The latter pin is carried by a bar 105 extending transversely of the intermediate support 34 and pivoted intermediate its ends to the latter on a pivot support (not shown) which is positionally adjustable longitudinally of the bar 105 and which may, for example, be of the form detailed in my copending application Serial No. 542,719 referred to above. The bar 103 is adjusted to an angle of inclination corresponding to a desired degree of taper on the work, and the bar 105 is rocked by a cam 106 (driven in timed relation with rotation of the spindle) for relief purposes. Details of the arrangement are disclosed in said copending application Serial No. 542,719.

I claim as my invention:

1. In a grinding machine, the combination of a base having a wheel support fixed thereon carrying a rotatively driven grinding wheel, a work support mounted on said base for movement transaxially of said wheel, a dresser support also mounted on said base for adjusting movement of the same generally transaxially of said grinding wheel, a screw having a nut threaded thereon with the latter restrained against rotation, said

nut being disposed for endwise movement with reference to said base, means mechanically connecting said work support to said nut for movement of said work support transaxially of said wheel in accordance with endwise movement of said nut, size control means for rotating said screw to move said nut endwise, and means connecting said dresser support to said screw for bodily endwise movement of the latter, together with said nut carried thereby, upon changes in position of said dresser support.

2. In a grinding machine, the combination of a base having relatively movable work and wheel supports mounted thereon, the latter carrying a rotatively driven grinding wheel, a dresser support mounted on said base for adjusting movement of the same toward and from said grinding wheel, a size control device, means rotatably journaling said device on said base while restraining the same against movement longitudinally of its axis of rotation, a rotatable size control shaft having a sliding coupling with said device, means connecting said shaft to said dresser support for bodily endwise movement of said shaft with said dresser support, a nut threaded on said shaft and restrained against rotation, and means for effecting relative movement of said work and wheel supports transaxially of said wheel in response to translation of said nut incident either to rotation of said shaft by said size control device or axial displacement of said shaft by said dresser support.

3. In a grinding machine, the combination of a base having a rotatively driven grinding wheel thereon, work and dresser supports disposed on generally diametrically opposite sides of said wheel, means pivoting said work support on said base for rocking of said work support toward and from said wheel about an axis generally paralleling that of the latter, means mounting said dresser support for adjusting movement of the same toward and from said wheel, a screw extending at right angles to the pivotal axis of said work support and having a nut threaded thereon with the nut restrained against rotation, means connecting said nut to said work support for rocking of the latter about its pivotal axis in accordance with axial displacement of said nut, size control means for rotating said screw to displace said nut axially, and means connecting said screw to said dresser support for bodily endwise movement of said screw, together with said nut carried thereby, in accordance with movement of said dresser support.

4. In a grinding machine, the combination of a base having a rotatively driven grinding wheel thereon, work and dresser supports disposed on generally diametrically opposite sides of said wheel, means pivoting said work support on said base for rocking of said work support toward and from said wheel about an axis generally paralleling that of the latter, means mounting said dresser support for adjusting movement of the same toward and from said wheel, a screw extending at right angles to the pivotal axis of said work support and having a nut threaded thereon with the nut restrained against rotation, means connecting said nut to said work support for rocking of the latter about its pivotal axis in accordance with axial displacement of said nut, and means connecting said screw to said dresser support for bodily endwise movement of said screw, together with said nut carried thereby, in accordance with movement of said dresser support, said last-mentioned means including a cylinder having a fluid operated piston slidable therein interposed

between said screw and dresser support for altering the displacement of said screw with reference to said dresser support in accordance with changes in position of said position within its cylinder.

5. In a grinding machine, the combination of a base having a rotatively driven grinding wheel thereon, work and dresser supports disposed on generally diametrically opposite sides of said wheel, means mounting said work support on said base for endwise translation of said work support in a path generally paralleling the axis of said wheel and for rocking of said work support toward and from said wheel about an axis generally paralleling that of the latter, an intermediate support located beneath said work support with the latter resting on it, means pivoting said intermediate support on said base for rocking motion about an axis coincident with the pivotal axis of said work support by restraining said intermediate support against endwise movement, means mounting said dresser support for adjusting movement of the same toward and from said wheel, manually operable means for shifting said dresser support toward and from said wheel, a screw located beneath said intermediate support and disposed at right angles to the common pivotal axis of said work and intermediate supports, a nut threaded on said screw and restrained against rotation, a depending leg on said intermediate support pivotally connected to said nut, whereby endwise movement of said nut effects rocking motion of said intermediate support and the work support resting thereon, size control means for rotating said screw to displace said nut axially, and means connecting said screw to said dresser support for bodily endwise movement of said screw, together with said nut carried thereby, in accordance with movement of said dresser support.

6. In a grinding machine, the combination of a first pair of supports adapted to carry, respectively, a work piece and a rotatively driven grinding wheel, a base, means stationarily mounting one of said pair of supports on said base and movably mounting the other for movement relative to the first-mentioned support in a direction transaxial of said wheel, a dresser support adjustable toward and from said wheel, means mechanically connecting said dresser support to the movably mounted one of said first pair of supports for moving the same upon adjustment in position of said dresser support, and means including a piston and cylinder type fluid actuator for altering the effective length of said mechanical connection between two limits corresponding to two limit positions of said piston within its cylinder to thereby shift said movable one of said first pair of supports independently of said dresser support.

7. In a grinding machine, the combination of a base, work and wheel supports, the latter carrying a rotatively driven grinding wheel, means pivotally mounting said work support on said base for rocking motion of said work support transaxially of said wheel, a dresser support adjustable toward and from said wheel, means mechanically connecting said dresser support to said work support for rocking of the latter upon adjustment in position of said dresser support, and means including a piston and cylinder type fluid actuator for altering the effective length of said mechanical connection between two limits corresponding to two limit positions of said piston within its cylinder, to thereby shift said work support with

reference to said grinding wheel independently of adjustment in position of said dresser support.

8. In a grinding machine, the combination of a base having relatively movable work and wheel supports mounted thereon, the latter carrying a rotatively driven grinding wheel, a screw having a nut threaded thereon with said nut restrained against rotation and free for endwise movement with reference to said base, size control means for revolving said screw, first connecting means for connecting said nut to one of said supports to shift the latter with reference to the other support upon endwise displacement of said nut, a dresser support adjustable toward and from said wheel, a second connecting means for connecting said dresser support to said screw to displace the latter endwise in accordance with movement of said dresser support, and a connector extensible or contractile at will interposed in said second connecting means and including a fluid actuated piston and cylinder.

9. In a grinding machine, the combination of a base having relatively movable work and wheel supports mounted thereon, the latter carrying a rotatively driven grinding wheel, a screw having a nut threaded thereon with said nut restrained against rotation and free for endwise movement with reference to said base, size control means for revolving said screw, first connecting means for connecting said nut to one of said supports to shift the latter with reference to the other support upon endwise displacement of said nut, a dresser support adjustable toward and from said wheel, a second connecting means for connecting said dresser support to said screw to displace the latter endwise in accordance with movement of said dresser support, and a connector extensible or contractile at will interposed in said second connecting means and including a fluid actuated piston and cylinder.

10. In a grinding machine, the combination of work and wheel supports having means thereon for respectively revolvably supporting a work piece and a grinding wheel, means pivotally mounting at least one of said supports for rocking motion of the same transversely of the work, a dresser, means supporting said dresser for adjusting motion generally transaxially of a grinding wheel carried by said wheel support, and means for effecting rocking motion of said pivoted mounting means proportionate to the motion of said dresser supporting means.

11. In a grinding machine, the combination of a base having a wheel support thereon carrying a rotatively driven grinding wheel, work and dresser supports located on substantially opposite sides of said wheel, means pivoting said work support on said base for rocking motion of the work carried by the work support generally transaxially of said wheel, means mounting said dresser support on said base for straight line in and out motion of the same with reference to said wheel in a direction substantially transaxial of the latter, and means for automatically rocking said work support through angular distances proportionate to changes in displacement of said dresser support with reference to said wheel.

12. In a grinding machine, the combination of a rotatably driven grinding wheel, a work support pivotally mounted to tilt toward and from the wheel, size control means for tilting said work support about its pivot, a dresser support movable toward and from said wheel, and means for tilting said support toward the wheel coincident with, and through a distance proportionate to,

each advance of said dresser support toward said wheel.

13. In a grinding machine, the combination of a base, a work support, a wheel support having a rotatively driven grinding wheel thereon, means pivotally mounting at least one of said supports on said base for rocking motion toward and away from the other generally transaxially of said wheel, means for adjustably securing said wheel support to said base for bodily adjustment of 10

said wheel and wheel support angularly with reference to a work piece carried by said work support, a dresser support movably mounted on said wheel support, means for adjusting said wheel support toward and from said wheel, and means for automatically rocking a pivotally mounted one of said work and wheel supports through a distance proportionate to each change in position of said dresser support.

AUGUST F. MARKUS.
